B. H. DAVIS

DEVICE FOR REMOVING PUMP LINERS AND VALVE SEATS

Filed April 12, 1923

UNITED STATES PATENT OFFICE.

BERNARD H. DAVIS, OF FULLERTON, CALIFORNIA.

DEVICE FOR REMOVING PUMP LINERS AND VALVE SEATS.

Application filed April 12, 1923. Serial No. 631,739.

To all whom it may concern:

Be it known that I, BERNARD H. DAVIS, a citizen of the United States, residing at Fullerton, in the county of Orange and State of California, have invented new and useful Improvements in Devices for Removing Pump Liners and Valve Seats, of which the following is a specification.

My present invention is an improved device for removing the liners and valve seats of pumps, and particularly those pumps that are utilized for pumping mud, sand, or the like from oil wells, the principal objects of my invention being to provide a relatively simple, practical device that may be readily inserted within a pump cylinder or valve seat, or the like, and which, when properly manipulated, will readily unseat the liner or valve seat therefrom.

It will be understood that pumps that are utilized for pumping mud, sand, and the like from well holes are commonly provided with removable liners, these being ordinarily straight cylinders, and with removable seats for the valves, these seats being ordinarily slightly tapered. The mentioned removable parts, and also bushings and similar elements, which may hereinafter be referred to simply as lining elements, very frequently become "rusted" into a pump, with the result that much time and labor have heretofore been involved in removing these parts when the same have become so worn as to render them unfit for further service.

It is an object of my invention to provide a relatively simple device comprising parts which may be easily and quickly engaged on the inner end of a lining element to withdraw the same from its working position within a pump, or the like, and which may also be used to put a new or old liner into position.

It is a further object of my present invention to provide means of the general character referred to which, although it may utilize the principle of the screw as well as that of the wedge in effecting an engagement of parts, shall nevertheless be, after its liner-engaging parts are properly disposed relatively to the liner element, entirely free from any wedging effect tending to distort such liner element, or tending to increase the frictional engagement between any lining element which is to be removed

and any outer tube or shell within which it may have been seated.

It is a further object of my invention to provide a rugged tool, which may preferably comprise ball-bearings, adapted to be made in standardized sizes, the work-engaging or grapple parts of my pullers being preferably of such configuration as to be easily collapsible for insertion through a liner element and adapted to be thereafter expanded into a substantially cylindrical form, with projecting lugs or flanges engaged beneath or beyond the back of the liner element which is to be removed, it being a merit of my preferred design that the wedging element by which my grapple is expanded may be at all times housed substantially therein, so that only a very limited bottom clearance (corresponding to the thickness of the mentioned lugs or flanges) is required to permit the engagement of said lugs or flanges.

Other objects of my invention will appear from the following description of a preferred embodiment thereof, and from the appended claims, taken in connection with the accompanying drawings, in which—

Figure 1 is a vertical section, with parts broken away, showing the relative position of parts of a puller of my design as the same is being inserted into a liner.

Fig. 2 is a corresponding view, showing the grapple of my puller expanded, and the lugs thereof engaged under the bottom of a liner.

Fig. 3 is a bottom view of a collapsed grapple, corresponding to Fig. 1.

Fig. 4 is a corresponding view of an expanded grapple.

Figs. 5 and 6 are perspective views, showing how a grapple of my design may be employed to pull a valve seat. Parts are broken away to show an alternative form of pulling head.

Referring in detail to the parts of those embodiments of my invention which I have chosen for purposes of illustration, 1 may be regarded as a pump cylinder, or the like, provided with a liner 2, which is to be removed, and the essential parts of my improved device for the removal thereof will now be described. A spanning element or yoke 3, which may be a casting provided with a central aperture 4 and a shoulder 5, is adapted to receive a drawbar 6 provided at

one end with means for imparting movement thereto, such as the tightening nut 7, and at the other end with a grapple of novel design, any preferred type of ball-bearings, 5 or the equivalent comprising rolling elements, being optionally provided in the form of a collar 8, adapted to engage respectively the shoulder 5 and the nut 7, or the equivalent, this nut being shown as having a 10 threaded engagement with the drawbar 6, and the respective legs of the spanning element 3 being adapted to engage the cylinder 1, from which the liner 2 is to be removed.

To effect the removal of the mentioned 15 liner, or the removal of a valve seat in the manner suggested in Figs. 5 and 6, I prefer to employ a grapple element comprising relatively swinging parts 9, shown as pivoted together at 10, and as adapted to be collapsed sufficiently to permit insertion 20 through a liner, in the manner shown in Fig. 1, these swinging parts being provided with inclined inner surfaces 9, adapted to be engaged by a head 11 upon the end of 25 the drawbar 6, the upper edge of the substantially cylindrical head 11 being preferably tapered, beveled or rounded, to facilitate its movement relatively to the inclined surface 9, in order that by a pull upon the 30 drawbar 6, the head 11 may be effective to wedge the swinging elements 9 apart, in the manner shown in Figs. 2 and 5, so that the lugs or flanges 12, upon the lower ends 35 of said swinging elements, may effectively engage under the bottom of a liner element, in readiness for the withdrawal of the same.

As will be obvious from an inspection of 40 Fig. 2, the first effect of the upward movement of the head 11 is a relative expansion of the swinging elements 9; and when these elements are expanded into a substantially cylindrical form, or into another form suitable to the interior configuration of a liner element which is to be removed, the body 45 of the head 11 being adapted to interfit therewith, no further wedging effect can be produced by further tension upon the drawbar; but since the upper ends of the swinging elements 9 are respectively provided 50 with abrupt or undercut shoulders 13, adapted to engage with a corresponding or substantially flat surface upon a corresponding shoulder T, located at the upper end of the head 11, a further upward movement of 55 the drawbar 6 can be effective only to draw a lining element from its seat. By continued rotation of the nut 7 upon the drawbar, a lining element, having been loosened or unseated in the manner described, may 60 be completely withdrawn.

When a grapple of my improved design is to be used for the unseating of cylindrical liners only, it is not necessary to provide the 65 same with slots such as are shown at N; but, when a valve seat 14 of the character shown

in Figs. 5 and 6 is to be withdrawn, such a valve seat being provided with integral transverse webs 15, it will be understood that the mentioned slots N will serve to allow clearance for the mentioned webs, permitting the lugs or flanges 12 to engage under the valve seat and to become effective in the withdrawal of the same. As best shown 70 in Figs. 1 and 2, the bottom of the head 11, which is integral with or secured to the drawbar 6, may be provided with a concavity 15^a, to provide room for parts of, or for elements associated with the valve seat 14, it being understood that any desired minor changes may be made in the design of parts 75 in order to adapt them to a particular use.

As will be obvious from an inspection of the figures, it is intended that the parts above mentioned shall be so proportioned that, when the head 11 shall be positioned substantially as shown in Fig. 1, the entire grapple is so collapsed that no diameter thereof shall exceed the internal diameter of the liner element which is to be withdrawn thereby; but that whenever this head is drawn into substantially the position shown in Fig. 2, it shall be operative to effect an expansion of the swinging elements 9 into the form of a cylinder, or into other form adapted to fit within a liner 95 element without producing lateral pressure thereon; and since the head 11 is adapted to permit a collapse of the entire grapple while confined therein, it will be obvious that, in order to permit of the positioning of a grapple of my preferred design, there is need of only sufficient clearance, beneath a liner, to permit the insertion of the lugs or flanges 12, the only effect of a subsequent advance of the drawbar 6 being the lifting 100 of a liner element from its seat.

In that form of my invention which is shown in Figs. 5 and 6, it will be noted that the head 11 is virtually a frustum of a cone, but in this form also I provide a shoulder T, having a flat top adapted to contact with the shoulders 13 upon the interior of the swinging elements 9.

Although I have described but two embodiments of my present invention, it will be understood that various features thereof may be independently used, and that various modifications may be made therein without departure from the spirit and scope of my invention as the same is indicated above and in the following claims; and also that my pullers may be used not only to remove liners but also to draw them into place (the drawbar 6 then extending through, for example, the opening 16) and for any other desired purpose.

What I claim is:

1. A puller comprising a drawbar, a grapple formed of swinging elements disposed about the drawbar, a head formed 130

- upon the drawbar, there being tapered and straight surfaces formed upon the interior of said elements, and means for pulling the drawbar causing said head to engage said tapered surfaces to expand said swinging elements and then to engage the straight surfaces, whereby the grapple may be pulled by the drawbar without further expanding said elements.
- 5 2. A puller comprising a drawbar, a grapple formed of swinging elements disposed about the drawbar, a head formed upon the drawbar and normally disposed within the grapple, there being frusto-conical and cylindrical surfaces formed upon the interior of the grapple, and means for pulling upon the drawbar, whereby said head may first engage the frusto-conical surfaces to expand the grapple and then engage the cylindrical surfaces whereby the grapple may be pulled by the drawbar without further expanding the grapple.
- 10 3. A puller comprising a drawbar, a grapple disposed about the drawbar, a head formed upon the drawbar and normally disposed within said grapple, said grapple having interior tapered surfaces adapted to be engaged by said head, means forming an abutment for the head adjacent the top of the grapple, and means for pulling said drawbar whereby said head may be caused to engage said tapered surfaces to expand
- 15 the grapple and then engage the abutment, whereby the grapple may be pulled by the drawbar without further expanding the grapple.
- 20 4. A puller comprising a drawbar, a head formed upon the drawbar, a grapple formed of swinging elements pivoted to each other above said head, there being tapered surfaces formed upon the interior of the grapple engageable by said head to expand the grapple, and means forming an abutment upon the grapple above said tapered surfaces whereby when the drawbar is pulled, the grapple will be expanded and then pulled by the drawbar upon engagement between said head and said abutment.
- 25 5. A puller comprising a spanning element, a draw bar adapted to be withdrawn through said spanning element, means adapted to be rotated upon said draw bar for withdrawing the draw bar from said spanning element, an anti-friction bearing disposed within said means and said spanning element, a head carried by said draw bar, a grapple composed of swinging elements having tapered interior surfaces engageable by said head, said swinging elements being pivoted together and secured about said draw bar.
- 30 In testimony whereof I have signed my name to this specification.
- BERNARD H. DAVIS.
